CLAIM

The ornamental design for a toy vehicle chassis, substantially as shown and described.

DESCRIPTION

FIG. 1 is a front side perspective view of a toy vehicle chassis showing my new design;

FIG. 2 is a top plan view;

FIG. 3 is a right side elevational view, the opposite being substantially a mirror image;

FIG. 4 is a front elevational view;

FIG. 5 is a rear elevational view; and

FIG. 6 is a bottom plan view.
